UNITED STATES PATENT OFFICE.

JOHN W. H. ADKINS, OF GALES CREEK, OREGON.

TYPE-WRITER ATTACHMENT.

1,181,982.

Specification of Letters Patent.

Patented May 9, 1916.

Application filed June 19, 1915. Serial No. 35,139.

To all whom it may concern:

Be it known that I, JOHN W. H. ADKINS, a citizen of the United States, residing at Gales Creek, in the county of Washington and State of Oregon, have invented certain new and useful Improvements in Type-Writer Attachments, of which the following is a specification.

The object of my invention is to provide a typewriter attachment, of improved construction, which will assist the operator in reproducing, or copying, on a sheet of paper on the typewriter platen, matter type-written or otherwise printed on a separate sheet of paper.

In other words, the object is to provide a device of this character which will present the maximum simplicity of construction, and which will be durable, as well as positive and automatic, in operation.

In the accompanying drawing, forming part of my specification and application, I have illustrated the preferred embodiment of my invention capable of carrying out the underlying principles thereof. In this drawing, like reference characters denote corresponding parts throughout the several views.

The several views of the drawing may be briefly described as follows:

Figure 1 is a fragmentary front elevation of a typewriter-frame and platen, showing my invention applied thereto; Fig. 2 is a section on the line A—B, Fig. 1; Fig. 3 is a side elevation; and Fig. 4 is a section on the line C—D, Fig. 1.

Referring, now, in detail to the drawing: 1 designates the typewriter platen of usual, or any preferred, construction, and forming no part of my invention.

2 is the platen-shaft, and 3, 3 the side members, of the typewriter-carriage frame. The platen-shaft 2 carries, toward one end thereof, and exteriorly of the right-hand end frame-member 3, Fig. 1, a sprocket-wheel 4, constituting a drive-wheel; and, at this end of said platen-shaft, the latter carries the usual knurled hand-wheel or twirler 5.

Suitably detachably carried by each of the typewriter frame-members 3, 3, desirably by means of a strap 6 and set-screws 6^a, is a vertically-inclined bracket 7, which is, preferably, a flat plate, the sides of which diverge from the bottom thereof upward, so that the bracket is of least width at the

bottom and of gradually increasing width to the top, as shown in Fig. 3. The top of each bracket 7 is arcuate or rounded, as shown, and connecting the two brackets 7, 7^a is a bridge-plate 8, curved in cross section throughout its length, as shown, to conform to the curvature of the tops of the brackets 7, 7.

The brackets 7, 7^a are each provided with a longitudinally-extending slot 9 disposed parallel with and adjacent one longitudinal edge thereof, as shown in Fig. 2. A plate 10 is disposed between the brackets 7, 7^a, and is mounted to slide in these slots 9, and constitutes a sliding guide, for a purpose hereinafter appearing. The sliding guide 10 is conveniently provided with a thumb-hold 11, for ready manipulation thereof. The brackets 7, 7^a are each also provided, near the tops thereof, with a longitudinally-extending, relatively shorter slot 12 (see Fig. 2), in which work the shafts 13 of a pair of juxtaposed, rotatable rollers 14, 14^a, which are normally maintained in contiguity and at the lower ends of the slots 12 by means of suitable springs 15, 15.

The slots 9 and 12 are parallel, and the slots 9, at the top, overlap a portion of the slots 12. The rollers 14, 14^a and the transversely-curved bridge-plate 8 are so relatively positioned that the latter constitutes, in function, a paper-guide to direct the paper downward as it passes through the rollers. That is, a horizontal line passing between the rollers will intersect the curved, depending plate 8.

Immediately exterior of the supporting-bracket 7^a, the shaft of the lower roller 14^a carries one member 16 of a clutch, which clutch-member 16 axially carries a clutch-member 18 loosely encircling the said shaft of the roller 14^a, and engageable with the other fixed clutch-member 16; whereby, when said two clutch-members are engaged, the sprocket-wheel 17, driven, through intermediate mechanism, by the driving-wheel 4, is revolved, thereby revolving the roller 14^a and, consequently, the contacting roller 14. Carried by the right-hand end (looking at Fig. 1) of the shaft 13 of said roller 14^a is a hand-wheel or disk 18, and, intermediate the axial hub 19 of said wheel 18' and one face of the sprocket-wheel 17 is a spiral spring 20 normally maintaining the sprocket-wheel 17, with its clutch-member 18 in engagement with the clutch-member 16.

Bearing against the other face of said gear-wheel 17 is one end of a leafspring depending, arcuate lever 21, pivoted, toward its upper end, to the right-hand supporting-bracket 7^a, near the top thereof. As is obvious, manual operation of the lever 21 will throw the clutch-member 18 out of engagement with the clutch-member 16. The upper portion, or shorter arm, of the lever 21 constitutes a handle. It is obvious that, by throwing the clutch-member 18 out of engagement with the clutch-member 16, rollers 14 and 14^a may be revolved independently of the platen 1, by twirling the thumb-wheel 18'. This is a very desirable construction, since it permits adjustment of the paper between said rollers, without rotating the platen.

Toward the lower end of the supporting-bracket 7^a is a shaft 22 carrying two sprocket-wheels 23, 24. Engaging the sprocket-wheels 4 and 23 is a sprocket-chain 25, and engaging the sprocket-wheels 17 and 24 is a sprocket-chain 26. It will now be seen that a sheet of paper disposed between the rollers 14, 14^a will, through the intermediary of the chain of sprockets, described, be fed in a step-by-step manner by the step-by-step line-spacing movement of the typewriter-platen 1.

The sliding-guide 10, which may be frictionally-held in the slots 9, 9, or held in any other manner, in any adjusted position, in said slots, is adjusted so as to display between said guide 10 and the roller 14^a a line of typewritten matter on the sheet of paper positioned between the rollers 14 and 14^a.

From the above description, taken in connection with the drawing, the many advantages of my invention will be apparent, especially to those skilled in the art to which the invention pertains. Among the advantages may be mentioned, simplicity of con-

struction, automatic operation, and convenience in attachment to any standard typewriter. The attachment adds no appreciable or material weight to the typewriter in connection with which it may be used, and is not cumbersome, and presents an attractive appearance, and is of great value in aiding the operator in copying matter on a typewriter.

For the purpose of complying with the provisions of the patent statutes of the United States, I have described, with some degree of particularity, the preferred embodiment of my invention; it being understood that all modifications that come within the terms of the appended claim, constitute no departure from the spirit of the invention, and come strictly within the scope thereof.

Having thus fully described my invention, what I claim as new and desire to secure by Letters Patent of the United States is:

In a copy-holder for typewriting machines, in combination with the typewriter platen and typewriter carriage-frame, supporting brackets removably secured to said frame, each bracket having a short, longitudinally-extending slot toward the top thereof and a relatively longer, longitudinally-extending slot parallel with said first-mentioned slot and, at its upper end, overlapping a portion of said first-mentioned slot, a pair of rotatable rollers having shafts mounted in said short slots and a sliding guide movable in said longer slots.

In testimony whereof, I affix my signature in presence of two witnesses.

JOHN W. H. ADKINS.
